(57) **CLAIM**

The ornamental design for an LED chip, as shown and described.

DESCRIPTION

FIG. 1 is a front elevation view of an LED chip showing my new design;

FIG. 2 is a rear elevation view thereof;

FIG. 3 is a left elevation view thereof;

FIG. 4 is a right elevation view thereof;

FIG. 5 is a top plan view thereof;

FIG. 6 is a bottom plan view thereof;

FIG. 7 is a perspective view thereof; and,

FIG. 8 is an exploded perspective view thereof showing portions that are not visible in the corresponding views.
